US00D360883S

United States Patent [19]

Ito et al.

[11] Patent Number: Des. 360,883

[45] Date of Patent: ** Aug. 1, 1995

[54] **DATA RECORDING AND REPRODUCING APPARATUS**

[75] Inventors: **Masafumi Ito**, Tokyo; **Koji Suzuki**, Tokorozawa; **Shigeru Hasegawa**, Kodaira, all of Japan

[73] Assignee: **TEAC Corporation**, Tokyo, Japan

[**] Term: **14 Years**

[21] Appl. No.: **19,658**

[22] Filed: **Mar. 8, 1994**

[30] **Foreign Application Priority Data**

Sep. 10, 1993 [JP] Japan 5-27529

[52] U.S. Cl. **D14/107; D14/164**

[58] **Field of Search** D14/100, 164, 107-109, D14/162, 167, 168; D13/162, 184, 199; D10/46, 81; 360/99.12; 361/622, 724, 727; 369/33; 312/208.1
